DESIGN FOR A CHAIR

Alfred F. Fukal, Chicago, Ill., assignor to The Cincinnati Ball Crank Company and The Shott Manufacturing Company, jointly, Cincinnati, Ohio, corporations of Ohio

Application February 14, 1941, Serial No. 99,007

Term of patent 7 years

To all whom it may concern:

Be it known that I, Alfred F. Fukal, a citizen of the United States and resident of Chicago, in the county of Cook and State of Illinois, have invented a new, original, and ornamental Design for a Chair, of which the following is a specification, reference being had to the accompanying drawing, forming part thereof.

I claim:

The ornamental design for a chair, as shown.

ALFRED F. FUKAL.
